METHOD AND APPARATUS FOR CONTINUOUSLY CRUSHING AND DISCHARGING CARBONIZED AND FOREIGN SUBSTANCES FROM WOOLEN AND WORSTED FABRICS

Homer C. Riggs, North Andover, Mass.

Application July 8, 1936, Serial No. 89,674

7 Claims. (Cl. 15—269).

This invention relates to improvements in method and apparatus for crushing carbonized substances, and other foreign substances, contained in woolen or worsted fabrics, and preferably also for removing the same from the material. In the preparatory treatment of wool for use in the textile art, burrs and other vegetable impurities in many instances adhere so closely to the fibre of the wool fleece that they are not removed in the usual process of scouring. Such burrs and impurities will not take dyes with which the wool or cloth made therefrom is treated and are therefore removed by carbonization. The common method of carbonization consists in exposing the cloth for a desirable period of time to the action of dilute solution of acid or to acid vapor after which the cloth is baked, thereby reducing the vegetable matter to carbon. In many instances these impurities retain substantially their original form though carbonized and in order to reduce them to the form of dust, which can be removed from the material, beating or crushing is employed.

Usually carbonizing is practiced in connection with the stock before it is converted into yarn, or else the yarn is carbonized before it is woven into fabric form. The present invention relates to improvements in processes for crushing and removing the carbonized and foreign substances from woven fabrics of woolen or worsted material. The present invention is particularly designed to remove the carbonized material and other foreign substances from woolen or worsted fabrics in a continuous process which may be operated at a far greater speed than processes heretofore employed.

The present method comprises continuously crushing and discharging carbonized and foreign substances from fabrics of woolen, worsted, or like material, by passing the material along a predetermined path at a predetermined rate, applying a crushing force to the material transversely of its path of movement, and causing relative reciprocations of the material and the force-applying means in a direction lengthwise of the path of movement of the material.

More specifically the method comprises forwarding the fabric along a predetermined path at a predetermined rate with a progressively advancing reciprocating movement and applying a compressive crushing force uniformly to the material transversely of its path of movement.

In the method of continuously crushing and discharging carbonized and foreign substances from woolen or worsted fabric, the web of fabric desirably is contracted transversely into rope form and the rope subjected repeatedly to compressive crushing forces uniformly applied transversely to the path of the rope as it is moved longitudinally with a progressively advancing reciprocating

movement so that the rubbing together of the folds of cloth produced by the transverse contraction of the rope will aid in the disintegration of the crushed, carbonized material, thus enabling it to be more readily discharged from the material by suction or beating.

By successively contracting the cloth transversely in advance of successive compressive crushing operations, the carbonized material will be reduced to finely powdered form or dust which can be readily removed from the material.

Suitable apparatus for performing the process above described is illustrated in the annexed drawings, in which,

Fig. 1 is a side elevation of a preferred form of machine with the side frame removed and the end walls shown in section along vertical planes respectively passing through the apertures through which the rope of cloth is introduced and delivered from the machine;

Fig. 2 is a plan view with the upper rolls removed to illustrate more clearly the path of the material passing through the machine; and

Fig. 3 is a vertical sectional view on lines 3—3 Fig. 1, viewed from the right toward the left, the rolls and certain other parts being shown in elevation.

The machine illustrated in the accompanying drawings comprises generally a series of pairs of upper and lower cylindrical crushing rolls presenting substantially smooth surfaces with means for guiding a web of fabric in rope form located in advance of the bites of each pair of crushing rolls, means for returning the rope of cloth in such manner as to pass through the pairs of rolls a second time, means for driving the rolls including a time-controlled reversing motor, and scrays located at the ends of the machine to receive accumulated folds of fabric adapted to permit progressively advancing reciprocating movements of the web of fabric for exerting substantially longitudinal tension upon the fabric as it is passed through the crushing mechanism.

The machine illustrated in the accompanying drawings comprises metal side frames 1 and 2 connected at their ends by suitable metal end plates 3 and 4, which desirably are of substantial width, and which may also be connected, if desired, by suitable transverse girders (not shown).

A series of lower cylindrical rolls 5 presenting smooth surfaces and having shafts or axles 6 are journaled in suitable bearings 7 in the side frames, the axes of the shafts being preferably arranged in the same horizontal plane. Complementary upper cylindrical rolls 8 also presenting smooth surfaces are provided with shafts or axles 9 and are journaled in suitable bearings 10 which are slidably mounted in suitable ways in the side frames, and are held in yielding contact by springs 11, the lower ends of which rest upon the bear-

- ings 10, the upper ends of the springs 11 engaging adjustable blocks 12 which are slidably mounted in said ways and are rotatably connected to the ends of adjusting screws 13 which are mounted in girders 14 extending longitudinally of the frame. The screws 13 are provided with hand wheels 15 by means of which the screws 13 may be rotated to adjust the pressure applied by the springs 11 to the bearings 10 of the upper rolls.
- 10 The lower rolls are driven by a reversing motor 16 which is controlled by suitable timing mechanism contained within a housing 17 which may conveniently be mounted upon the base of the reversing motor. The shaft 18 of the motor is provided with a suitable sprocket 19 which drives a chain 20 which in turn drives a sprocket 21 fixedly secured to the shaft 6 of one of the lower rolls 5. As illustrated, the chain 20 drives one of the intermediate lower rolls.
- 20 The lower rolls are all driven at the same speed, the shaft 6 of each roll being provided with a similar sprocket 21x which is actuated by a chain 22 which engages all of the sprockets upon the respective shafts and which may be provided with a usual tightener (not shown) to insure continuous engagement of the chain 22 with all of the sprockets upon the shafts of the lower rolls.
- 25 The web of fabric 23 is supplied from any suitable source, such as a truck, to driven guide rolls (not shown) from which it is delivered to a spray 24 which may be conveniently supported upon a frame 25 in proximity to the front end of the machine. The spray is provided with a curved bottom and an upwardly inclined side leading toward the front end of the frame and the cloth passes therefrom through a suitable guide, such as a pot-eye 26 which condenses the web transversely into rope form. The rope then passes
- 30 through an aperture 27 in the front plate 3 of the frame, thence between the successive pairs of cylindrical compressive crushing rolls 8 and 5. Similar guides, preferably in the form of pot-eyes 28, are located between each pair of rolls, thereby
- 35 condensing the fabric which has been flattened out during its passage between the rolls, so that new folds are produced in advance of each pair of rolls and the friction of the faces of the folds of fabric against each other, as the fabric is
- 40 passed through the successive pairs of rolls, serves further to disintegrate the carbonized material contained in the fabric. The guides or pot-eyes may be supported in any suitable manner as by brackets mounted upon the side frames and projecting a desirable distance inwardly therefrom. Desirably the fabric is passed in a straight line through the successive pairs of rolls adjacent one end thereof and after passing between the last
- 45 pair of rolls of the series is guided downwardly around the lower roll, thence forwardly through a series of pot-eyes 29 arranged to carry the rope of cloth diagonally of the machine and over the lower roll near its opposite end, thereby causing the rope to pass again between the upper and lower rolls of the first pair, and thence between the upper and lower rolls of the succeeding pairs.
- 50 Suitable guides or pot-eyes 30 are located in advance of each pair of rolls and again condense the fabric laterally as it approaches each pair of rolls. The fabric is finally delivered from the last pair of rolls through a guide, preferably a pot-eye 31, to a spray 32 mounted upon a suitable frame 33. The cloth is delivered from the spray through a pair of driven rolls 34 and 35 to a suitable reel, receptacle or conveyer (not shown).

In order to remove the pulverized carbonized material means are provided for producing a suction which will act upon the material as it passes from one pair of rolls to the next. In the preferred construction a hopper is provided which 5 preferably comprises sheet metal sides 36 and 37, the upper edges of which are secured to the side frames and which converge downwardly and communicate with the tubular conduit 38 which leads to the eye of a fan 39, so that the draft produced by the fan through the hopper will remove the fine carbonized material which drops into the conduit 38 and will also provide a suction throughout the machine which will aid in removing the carbonized material from the fabric. 10 15

While the machine above described is particularly designed and adapted for removing carbonized material from a rope of fabric, it will be understood that the web of fabric may be passed through the machine in flat form, with suitable 20 guides in advance of the respective pairs of rolls, or that the machine may be adapted to treat slivers of wool or worsted or even yarn in the manner above described.

The reversing motor is provided with controlling mechanism which causes the motor to rotate a predetermined number of times in a direction to advance the material forwardly and then reverse automatically for a predetermined lesser number of revolutions, so that the fabric is reciprocated back and forth between the rolls with a progressively advancing movement, thereby causing the material to pass several times through the bite of each pair of rolls, for example, the motor may be so controlled as to rotate the rolls fifteen 35 revolutions in a direction to advance the material, then automatically reverse and rotate the rolls ten revolutions in a direction to retract the material, then again reverse and rotate the rolls fifteen revolutions in a direction to advance the 40 material and so on thereby giving a net advancing movement of the fabric corresponding to five revolutions of the rolls.

A suitable timed reversing motor which has been successfully employed as above described is 45 a Westinghouse type C W three-phase slip ring motor, forty-cycle, five hundred fifty volt, having an automatically time-operated reversing switch provided with a replaceable cam by means of which the timing of the reversing motor may be 50 adjusted.

By the substitution of suitable cams in the controlling mechanism for the reversing motor, which may be of a usual type, any desired speed of delivery of the material may be provided. Inasmuch as the sprays at the opposite ends of the machine permit the accumulation of a number of folds of the fabric, no substantial tension is placed upon the web of fabric by the reversal of movement of the web and inasmuch as the net advancing movement of the web is uniform the rolls, which feed the material to the machines and which deliver it from the machine, may be driven at a predetermined constant speed corresponding to the net advancing movement of the 60 65 material.

By reason of this construction therefore continuous crushing and discharging of carbonized and foreign substances from the material will be produced and by uniting the successive webs of fabric end to end the process may be carried on any desired length of time.

The operation of the machine is much faster and more efficient than that of usual machines and processes heretofore employed for the pur- 70 75

pose of crushing and discharging the carbonized and foreign substances from woolen and worsted materials and fabrics. Furthermore, as each unit of length of the fabric is repeatedly acted upon 5 in the manner above described a more uniform and complete removal of the carbonized material is effected than in previous machines and processes.

It will be understood that the apparatus particularly shown and described herein is of an 10 illustrative character and not restrictive and that various modifications may be made within the spirit and scope of the following claims.

Having thus described the invention, what is 15 claimed as new, and desired to be secured by Letters Patent, is:

1. The method of continuously crushing and discharging carbonized and foreign substances from woolen or worsted fabric, which comprises 20 contracting the fabric into rope form, forwarding said rope material along a predetermined path at a predetermined rate, successively applying compressive crushing forces at predetermined spaced intervals to said rope transversely 25 of its length re-forming the material into rope form between each crushing operation and causing relative reciprocating movements of said rope and said force-applying means in a direction lengthwise of said rope.

2. A machine for continuously crushing carbonized and foreign substances contained in 30 woolen or worsted fabrics, which comprises a set of smooth, cylindrical crushing rolls having cylindrical surfaces, guiding means located in front of said rolls for contracting the material into rope form and guiding the same to the bite of said rolls, means for rotating said rolls alternately in forward and reverse directions so timed as to reciprocate the material in the bite of the 35 rolls and progressively to advance the material at a predetermined rate.

3. A machine for continuously crushing carbonized material and foreign substances contained in woolen or worsted fabrics, which comprises 40 a frame, a series of sets of cooperating smooth, cylindrical crushing rolls mounted in said frame at predetermined spaced intervals, means in front of each set of crushing rolls for contracting the material and guiding the same in rope form to the bites of the respective sets of rolls, and means for alternately rotating all 45 of said sets of rolls in directions to reciprocate said material simultaneously through the bites of all of said rolls and so timed as progressively to advance the material at a predetermined rate.

4. A machine for continuously crushing carbonized material and foreign substances contained in woolen or worsted material, and the like, which comprises a frame, a series of sets 50 of cooperating crushing rolls having cylindrical surfaces mounted in said frame, means in front of each set of crushing rolls for contracting the material and guiding the same in rope form to the bites of the respective sets of rolls, means for alternately rotating all of said sets of rolls in directions to reciprocate said material simultaneously through the bites of all of said rolls and so timed as progressively to advance the material 55 at a predetermined rate, a housing beneath said sets of rolls, and means for producing a suction of air through said housing to remove and discharge the crushed carbonized and foreign substances from said material.

5. A machine for crushing and removing carbonizing and foreign substances from a web of woolen or worsted fabric, and the like, which comprises a frame, a series of pairs of upper and lower cooperating cylindrical crushing rolls 60 mounted thereon rotatable about horizontal axes lying respectively in the same horizontal planes and spaced apart, pot-eyes in front of each set of rolls for contracting and guiding the fabric in rope form to the bites of the respective pairs of rolls, means for alternately rotating all of said pairs of rolls in forward and reverse directions so timed as to reciprocate said web through the bites of the respective pairs of rolls and progressively to advance said web at a predetermined 10 rate, means for freely supplying the fabric to the first set of rolls, a scrap positioned to receive and collect the fabric delivered from the last pair of rolls, and means for continuously withdrawing said web of fabric from said scrap at 15 a predetermined rate.

6. A machine for crushing and removing carbonized and foreign substances from a web of woolen or worsted fabric, and the like, which comprises a frame, a series of pairs of upper 20 and lower cooperating cylindrical crushing rolls mounted thereon rotatable about horizontal axes lying respectively in the same horizontal planes and spaced apart, pot-eyes in front of each set of rolls for contracting and guiding the fabric 25 in rope form to the bites of the respective pairs of rolls, means for guiding the rope of fabric from below the lower roll of the last set diagonally beneath said rolls to the bite of the rolls of the first set, and pot-eyes intermediate of 30 said pairs of rolls for guiding the rope to the bite of the respective rolls whereby the rope will be passed again through the bites of each pair of rolls, means for alternately rotating all 35 of said pairs of rolls in forward and reverse 40 directions so timed as to reciprocate said web through the bites of the respective sets of rolls and progressively to advance said web at a predetermined rate.

7. A machine for crushing and removing carbonized and foreign substances from a web of woolen or worsted fabric, and the like, which comprises a frame, a series of pairs of upper and lower cooperating crushing cylindrical rolls mounted thereon rotatable about horizontal axes 45 lying respectively in the same horizontal planes and spaced apart, pot-eyes in front of each set of rolls for contracting and guiding the fabric in rope form to the bites of the respective pairs of rolls, means for guiding the rope of fabric 50 from below the lower roll of the last set diagonally beneath said rolls to the bite of the rolls of the first set, and pot-eyes intermediate of said pairs of rolls for guiding the rope to the bite of the respective rolls whereby the rope will be 55 passed again through the bites of each pair of rolls, means for alternately rotating all of said pairs of rolls in forward and reverse directions so timed as to reciprocate said web through the bites of the respective sets of rolls and progressively to advance said web at a predetermined rate, and scrays located respectively in front of the first pair of rolls and rearwardly of the second pair of rolls to receive the web of fabric 60 between said rolls without imposing substantial tension thereupon.

HOMER C. RIGGS.
